UNITED STATES PATENT OFFICE.

HERMAN C. BREHMER, OF PHILADELPHIA, PENNSYLVANIA, ASSIGNOR TO H. W. BUTTERWORTH & SONS, A CORPORATION OF PENNSYLVANIA.

MOISTENING DEVICE FOR TEXTILE MACHINERY.

Application filed July 13, 1923. Serial No. 651,270.

To all whom it may concern:

Be it known that I, HERMAN CHRISTIAN BREHMER, a citizen of the United States, and resident of Philadelphia, county of 5 Philadelphia, and State of Pennsylvania, have invented an Improvement in Moistening Devices for Textile Machinery, of which the following is a specification.

My invention has for its object the construction of a spraying device for vaporizing water and treating a traveling web of fabric thereby in a continuous manner, and more particularly, my object is to so construct the spraying devices that uniform action may 15 be assured and the amount of the spray or vapor accurately adjusted to suit the requirements of the fabric being treated.

With the above and other objects in view, the nature of which will be more fully understood from the description hereinafter, the invention consists in the novel construction of moistening devices for textile machinery, as hereinafter more fully described and defined in the claims.

Referring to the drawings: Fig. 1 is a side elevation of a fabric moistening machine embodying my improvements; Fig. 2 is a plan view of the same; Fig. 3 is a horizontal sectional view of the spraying apparatus proper, taken on line 3—3 of Fig. 4; Fig. 4 is a vertical section of the same taken on line 4—4 of Fig. 3; Fig. 5 is a vertical transverse section of the same, taken on line 5—5 of Fig. 4; Fig. 6 is an end view of a modified arrangement of spraying means for simultaneously treating opposite sides of the fabric and embodying my invention; Fig. 7 is a sectional view of one of the spray nozzles, more particularly illustrating its mode of attachment for varying the spray; and Fig. 8 is a perspective view of a detail of the nozzle of Fig. 7.

2 is the main frame of the machine and is provided at the top with transverse bars 3, 3, over which the fabric 4 is guided. Ordinarily, the fabric is supplied to the machine over suitable tension bars 5, one of which alone is shown, thence under a guide roll 6, thence over the bars 3, 3, thence under the tension and winding roll 7 by which it is wound upon a mandrel 8 in roll form, as indicated at 9. Downward pressure is applied upon the mandrel by suitable devices 10, well known in the art, and the lower portion of which alone is shown, such devices

applying as much pressure as may be desired between the cloth roll 9 and the surface of the feeding and tension roller 7, whereby the roll of fabric 9 may be wound under any desired tension. The roller 7 may be driven 60 in any suitable manner, but, as shown, is provided with a gear 11 which is rotated by a pinion 12 on a shaft 13, driven by a belt wheel 14 through a suitable clutch device 15. Any other suitable driving means may be 65 employed, if so desired.

End bars 3^a may extend between the transverse bars 3, 3, at each end, and may continue downward to form the end of a box-like space, said space being closed on the 70 remaining sides by upright wall portions 3^b. The bottom of this space is closed by a shallow tray structure 16 in which the lower parts of the box-like structure rests, as indicated in Fig. 5, the said shallow tray itself 75 being supported by a suitable support 17 extending down to the floor.

The spraying apparatus proper is more fully disclosed in Figs. 3, 4, 5 and 7, and special reference will now be made to these 80 figures. Three tanks 18, 19 and 20 are arranged in parallel relation transversely of the machine above the tray 16 and supported upon transverse supports 21, (Figs. 4 and 5), resting upon the bottom tray 16, whereby 85 free space is provided under said tanks for permitting the flow and escape of water which may be precipitated into the tray. The tanks 18, 19 and 20 are separated from each other to provide spaces 22 between them 90 in which the spray nozzles are arranged, together with air pressure supplying means. The tanks 18, 19 and 20 are provided, near one end, with overflow pipes 23 which are made conical at the bottom to fit drain outlets 95 24, said pipes 23 insuring a definite level of the water in the tanks and at the same time to permit, when necessary, the full draining of the tanks. The drain outlets 24 extend through large apertures 25 in the bottom of the tray 16 and discharge into a transverse trough 26 which is common to all three drain outlets from the respective tanks and also receives the drainage of the spray water which may be received in the tray 16, as all 100 of said apertures 25 from the tray also discharge into the transverse trough 26. The trough 26 has a drain or discharge 27 for leading the water away to the waste pipe. Secured in the two side walls of the middle 105 110

tank 20 and in the adjacent side walls of the tanks 18 and 19 are angular water pipes 28, the lower ends of which lead downward toward the bottom of the tanks and the upper horizontal ends 28^a project laterally through the tank wall and terminate in a nozzle part 29. The horizontal portion 28^a is screw threaded and extends through a hole 31 in the tank wall of considerable higher length than the diameter of the pipe, so that it may be adjusted vertically. If desired, this hole may simply be a round hole of larger diameter than the pipe. 32 are nuts screwed on the pipe and 33 are packing washers between the nuts and the tank wall, whereby when the nuts are screwed on the pipe 28^a against the wall, they clamp the pipe definitely in position upon the wall but with capacity for vertical adjustment.

20 The air blast nozzle 30 is formed on the upper end of a screw threaded pipe 35 which is screwed downward into a transverse air conduit 36, said air conduit being rigidly positioned in the space 22 between the tanks.

25 To insure accuracy in the right angled arrangements of the nozzles 29 and 30, I provide a right angled frame 37, the two arms of which are slidably fitted over the respective nozzle pipes 28^a and 35 to position them in alignment in the same plane. The arms of this frame 37 are slotted and nuts 38 are provided in the slots and respectively screwed upon the threaded portions of the nozzle pipes 28^a and 35, all of which is shown in Fig. 7. The angle frame is further slotted in the plane of the nozzles and from one of the apertures to the other, as indicated at 39 in Fig. 8, and the two sides 40 thus provided may be drawn together by a clamping screw 41 for tightening said frame upon the nozzle pipes when the adjustment has been made. It will now be understood that by the adjustment of the nozzles 29 and 30, a coarser or finer spray may be produced, this also being dependent somewhat upon the amount of air pressure. The nozzle pipe 35 is screwed firmly into the air conduit 36 and is normally immovable thereon. If the nuts 32 of the nozzle pipe 28^a are loosened and the clamping screw 41 also loosened, the nuts 38 may be adjusted to raise and lower the nozzle 29 and to adjust it horizontally to or from the nozzle 30, and when the proper adjustment is made, the clamping screw 41 is tightened and thereafter the nuts 32 are tightened upon the side wall of the tank.

60 As will be seen, there are a very large number of these spray nozzles and all of them are constructed in the manner just described, so that they have capacity for adjustment. As the spray nozzles have very small apertures, it is important that no lint or fine material floating in the water shall be permitted 65 to find access to them and, therefore, if de-

sired, the lower ends of the pipes 28 may each be fitted with a gauze strainer 28^a held in place by a suitable sleeve 28^b. In lieu of having a strainer for each of these nozzles, the water supply pipe 42 for delivering water to the tanks may be supplied with a suitable strainer 43^a (Fig. 5), and this is preferable where the tanks 18, 19 and 20 are sealed at the top, because the expense of the individual strainners 28^a may be thus avoided. As shown in Figs. 4 and 5, the several tanks 18, 19 and 20 are provided with removable covers 43 which are preferably inclined to shed the spray water which may fall upon them. These covers effectually prevent any fine lint or fibers which may fall from the fabric being treated from finding their way into the water contained within the tank.

20 The air conduits 36 are preferably formed of light castings of rectangular cross section and are clamped at each end into the end plate 44 which may be formed as a continuation across the air spaces 22 of the ends of the tanks 18, 19 and 20, so that it is definitely positioned in reference to the water tanks. In the special means for clamping these conduits to the end walls 44, I prefer the construction illustrated in the right hand of Fig. 4, wherein a flanged bushing 45 is secured to the end of the conduit 36 by being soldered therein and said bushing screw threaded upon the inside for receiving a pipe nipple 46 leading from an elbow 47 of an air supply pipe 48, said nipple having a nut 49 for clamping the end plate or wall 44 between it and the flange of the bushing 45, to make an air tight joint and also a frame connection for the air supplying pipe to the conduit. The same construction is employed at each end of the conduit 36, and where the length of the conduit 36 is great, I provide further means of supplying air under pressure to the interior of the conduit and this construction is clearly illustrated in Figs. 3, 4 and 5. In general, this part of the improvement relates to special means extending through the outer tanks 18 and 19 for delivering air directly into the conduits 36, and as each of these means are the same, it will suffice to describe the means as applying to one of the conduits only.

25 The interior of the tank 19 is provided with a transverse tubular part 50 which is definitely secured therein in any suitable manner but so as to provide a tubular passage transversely through the tank. Extending through this tubular passage thus formed is an air supply pipe 51 which screws into a head 52 bolted to the conduit by bolts 53 and having an inward tubular extension 54 extending transversely across the conduit for bracing against the strain of the bolts, said part apertured to permit the entrance of the air into the conduit. A nut 55 on the pipe 51 may be employed for firmly posi-

tioning the parts in respect to the tank. Any other suitable manner of supplying air to the conduit may be employed, if so desired, in lieu of that shown.

- 5 The description thus given in connection with the tank 19 equally applies to the construction in connection with the tank 18, the only difference being that the air supplying pipes 51 enter in opposite directions.
- 10 It will be understood from Fig. 4, that when the tubular part 50 is introduced transversely of the tanks 18 and 19, for permitting the passage of the air pipes 51, an obstruction will have been introduced for
- 15 the downward extension of the nozzle pipes 28 in the vicinity of said tubular passage, and consequently said pipes are bent laterally and downward, as indicated in Fig. 4, and, moreover, as the pipe 28 immediately
- 20 above the tubular part would interfere with the corresponding pipe next to the right in Fig. 4, it is necessary to extend this pipe further to the rear, as at 28^c in Fig. 3, so that it not only clears the tubular part 50,
- 25 but also the pipe 28 of the nozzle next adjacent.

While I do not limit myself to any particular means for supplying compressed air to the conduits and their nozzles, the particular means preferred is shown more fully in Figs. 1 and 2.

56 represents a pressure blower and is driven from the power shaft 13 by a belt and pulley drive 57. The compressed air is delivered into a main 58 which, in turn, delivers to a head 59 from which extend pipes 60 provided with butterfly controlled valves 61, of any suitable construction, and said pipes 60 extend upwardly and connect with the pipes 51 leading to the middle of the conduits 36 before described and also with pipes 48 leading to the ends of the said conduits 36. Any other suitable arrangement of air supply to the conduits may be employed, if so desired. The valves 61 may be adjusted to increase or decrease the air pressure in respect to either of the conduits 36, as may be desirable.

The water supply pipe 42 has branches opening into each of the tanks 18, 19 and 20, as indicated at 42^a, 42^b and 42^c respectively, and as the tank 20 has double the number of spray pipes 28 and, therefore, must handle twice the amount of water as compared with the tanks 18 and 19, the water supply nozzle 42^c is made larger than those of the tanks 18 and 19 and similarly, the overflow pipe 23 is desirably made larger to prevent any abnormal rising of the water level in said tank 20. It is the intent and purpose that the water levels shall be in substantial alinement with the nozzles 29 so that there will be no appreciable dripping from the said nozzles when the air pressure is not on.

Interposed between the fabric passing over the transverse guide bars 3, 3, and the water spraying devices are arranged hinged doors 62 which form a roof or closure over the water spraying devices and shield them against depositions of dust or lint which may be floating in the atmosphere when the machine is out of operation but which are capable of being raised to open communication between the spraying devices and the fabric to the desired extent when in operation. To enable the adjustment, the hinged doors are provided with leather straps 63 having holes similar to any trunk strap and which may be hooked over pin 64 in the side of the frame 2 for holding the doors in open position. When these doors are extended upward, they provide free passage for the water spray to reach the fabric. In some cases, the doors 62 may be formed in two leaves for more fully opening the passage to the fabric where the supporting guides are not sufficiently high to allow the doors to fully open. The extent of opening also controls the amount of moisture which reaches the fabric and, therefore, ordinarily, the doors are not fully opened, but are adjusted to permit sufficient access to the fabric for the purpose required and are, therefore, in a measure a simple adjusting device which controls the amount of moistening or humidification of the fabric without the necessity of changing the air blast pressure.

While in most cases it will suffice to spray one side only of the fabric and especially where the fabric is of a relatively thin texture, in other cases it is desirable that the fabric shall be sprayed or moistened upon both surfaces and this may be accomplished at the same time by employing spraying devices arranged, as illustrated in Fig. 6. In this case, there are four sets of spray nozzles, as is the case in Fig. 5, but these sets are separated by arranging two sets below the fabric to spray upwardly and two sets arranged above the fabric to spray downwardly. In this case, the arrangement below the fabric would be as if the middle tank 20 and its spraying devices were removed and the two tanks 18 and 19 moved closer together, with a common air conduit 36, such as is indicated in dotted lines in Fig. 6. In the case of the upper spraying means, the construction would be similar to that below the fabric except that the spray nozzles 30 and the conduit 36 are inverted, so that the air blast is downward instead of upward. In this case, I have indicated the two tanks at 18^a and 19^a, with the air space and conduit 36 between them. On account of the tank being largely below the spray nozzles, I prefer that the opposing faces of the two tanks shall be inclined away from each other, as at 22^a, to

provide a widening passage for the spray to enable it to more fully reach the fabric. Otherwise, in general construction as to details, the means for supplying water and spraying it is of the same character as illustrated in Fig. 5, though in the case of the outer set of spray devices, there would be no tray corresponding to 16 below the tanks, as the presence of such a tray would 5 obstruct the passage of the spray to the cloth. Furthermore, as all of the spray from the upper set of spraying devices will reach the fabric on account of the gravity action, aside from the air blast, the amount of the 10 air blast may be somewhat reduced by manipulating the valve 61 which would control the air supply to the air conduit thereof, whereby a lesser air blast may be provided for the upper spraying devices than 15 that employed with the lower spraying devices.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood 20 that I do not restrict myself to the details, as the same are susceptible of modification in various particulars without departing from the spirit or scope of the invention.

Having now described my invention, 25 what I claim as new and desire to secure by Letters Patent is:—

1. In a spraying device for textile machinery, the combination with means for guiding a fabric in web form, of spraying means arranged below the fabric, comprising a plurality of parallel tanks separated at a distance apart, an air conduit arranged in the space between the tanks, pressure devices for supplying air to the conduit, two 30 sources of air nozzles opening upward from the air conduit, and angular pipes arranged in each of the tanks extending through the side walls thereof and terminating in nozzle portions adjacent to the air nozzles whereby 35 the air blast causes the water from the tanks to be sprayed from the last mentioned nozzles and projected upwardly between the tanks toward the fabric, said tanks also provided with means for supplying water 40 thereto, and overflow devices for maintaining a substantially constant level of water within the tanks.

2. The invention according to claim 1, 45 wherein each angular water pipe and its spray nozzles is adjustably clamped both to the tank wall and to the air nozzles extending upwardly from the conduit.

3. The invention according to claim 2, 50 wherein the adjustable connection between the two nozzle portions comprises screw

threaded pipes adjacent to the nozzles, an angular frame slidably fitted over the screw threaded portions to hold the nozzles at an angle to each other, adjustable nuts carried by the frame and respectively screwed upon the threaded pipe portions, and clamping means for clamping the frame tightly to the threaded pipe portions when the proper adjustment is made, and wherein further, the angular pipe extends through an enlarged aperture in the side of the tank and is provided with clamping nuts and packing washers upon opposite sides of the tank wall to permit adjustment of the pipe relatively to the walls and at the same time insure a water tight joint.

4. The invention according to claim 1, wherein the bottom of each of the angular pipes extending down into the tanks is provided with a screen and each of the tanks is provided with a cover to prevent lint from the fabric finding its way into the water within the tanks.

5. The invention according to claim 1, wherein further, a large tray is provided in which the tanks are positioned and supported above the bottom, said tank provided with apertures through which the tanks may drain as well as the tray itself, and a drain trough arranged below the tray and common to all of the apertures therein and to the overflow drainage from the respective tanks.

6. The invention according to claim 5, wherein further, the covers of the tanks are made inclined to insure water received thereon passing to the tray, a surrounding casing extending from the fabric down to the tray for confining the spray and adjustable doors arranged within the confining space to form a closure above the tanks which may be opened when the spray is required to reach the fabric and which moreover may control the extent of surface of the fabric exposed to the spray at any instant of time.

7. The invention according to claim 1, wherein valve mechanism is provided between the source of air pressure and the air conduit supporting the spray nozzles for controlling the air pressure delivered into the conduit to insure uniform spray blast to the series of nozzles for each of the tanks.

8. The invention according to claim 1, wherein the tanks are connected at each end by a transverse plate, and wherein further, the air conduit extends substantially the full length of the tanks and terminates adjacent to each of the plates, air pipes leading from the source of air pressure and communicating through the end plates with each end of the conduit, and clamping means for clamping the pipes to the respective ends of the nozzle supporting air conduit, the

conduit being of less width than the distance between the two tanks to provide an air space around the conduit and also a passage for descent of water.

5 9. The invention according to claim 8, wherein the air pipes at each end of the air conduit are united in a single pipe leading to the source of compressed air, and a valve device in said single pipe for simultaneously controlling the air pressure to the opposite ends of the conduit.

10 10. The invention according to claim 8, wherein further, one of the tanks is provided with a transverse tubular passage extending 15 through it from side to side, an air pipe extending through the tubular passage of the tank and communicating with the interior of the air conduit substantially midway between its ends, and a pipe leading from the

20 pressure devices and common to all three air pipes which communicate with the nozzle supporting conduit.

25 11. The invention according to claim 10, wherein further the pipe between the pressure devices and the plurality of branching pipes leading to the air conduit is provided with valve devices for controlling the air pressure.

30 12. In a spraying means for textile material, the combination with means for guiding textile material, of a spraying device arranged below it and consisting of three parallel tanks united at their ends by transverse walls providing confined air spaces between the tanks open at the top and bottom, two air conduits arranged in the air spaces between the tanks and secured at each end to the connecting walls between the tanks, means for supplying compressed air to the 35 40 air conduits, two series of air nozzles arranged in parallel rows along the top of each of the conduits, water spraying nozzles for each of the air nozzles and provided with angular water supply pipes extending laterally and downwardly within the respective

tanks, and wherein the outer tanks each have a single series of water spraying pipes and nozzles while the middle tank is provided with two series of such water supplying pipes and nozzles, the nozzles of each series pointing in opposite directions and cooperating with air nozzles of the respective air conduits, the said spray nozzles producing upwardly directed water sprays against the under surface of the fabric, means for supplying water to the respective tanks, overflow means for maintaining a definite level of water in said tanks and permitting the surplus water to drain off, a drainage tray arranged at a distance below the respective tanks for receiving water which may be unabsorbed by the fabric, and a confining chamber surrounding the tanks and extending toward the fabric.

55 13. The invention according to claim 12, wherein further separate air controlling means is provided for each of the air conduits.

60 14. The invention according to claim 1, wherein further, a second plurality of water tanks are arranged above the first mentioned tanks and between which upper and lower tanks the fabric passes, said upper tanks further provided with an intermediate space in which an air conduit is arranged provided 70 with downwardly extending air nozzles, said conduit also provided with angular water pipes whose upper ends terminate in nozzle in juxtaposition with the air nozzles, whereby a downwardly directed water spray is 75 80 obtained upon the fabric.

15. The invention according to claim 14, wherein further, the lower adjacent portions of the upper tanks are inclined away from each other to form a downwardly flaring spray passage between the tanks and below the nozzles thereof.

85 In testimony of which invention, I hereunto set my hand.

HERMAN C. BREHMER.
